READILY RELEASEABLE LOOP RETAINER

Filed March 31, 1949

FIG. 4

INVENTOR
JOHN R. AYERS
John R. Ayers

ATTYS

the loop when the end portions are brought into alignment with each other, said other end portion having its extremity deflected outwardly in the general plane of the loop by less than 90° and adapted to extend into the space between adjacent convolutions of the coil, the angular relationship of the end portions and the resiliency of the loop causing said outwardly deflected extremity to be forced outwardly between adjacent convolutions of the coil and thereby releasably latch the loop closed in any adjusted position.

JOHN R. AYERS.
